UNITED STATES PATENT OFFICE.

JAMES MCKENZIE AND JOHN C. MILLAR, OF TROY, NEW YORK.

IMPROVEMENT IN FULLING-MILLS.

Specification forming part of Letters Patent No. 36,013, dated July 29, 1802.

To all whom it may concern:

Be it known that we, JAMES MCKENZIE and JOHN C. MILLAR, of Troy, in the county of Rensselaer and State of New York, have invented certain new and useful Improvements in Fulling-Mills for Fulling Cloth; and we do hereby declare that the following is a full description of the same, reference being had to the annexed drawings, and to the letters of reference marked thereon, making part of this specification, in which—

Figure 1 is a perspective view of the machine. Fig. 2 is a vertical sectional view. Fig. 3 is a view of the series of fulling-rollers, hidden from view in Fig. 1 by the fulling-plates; and Fig. 4 is a view of an elastic or yielding core-roller or cloth-holder with cloth or blankets arranged around it in readiness for the operation of fulling.

The same letters refer to like parts in each of the figures.

In this invention our object has been to produce a fulling-machine that shall full or mill the cloth effectually in at least one-half of the time heretofore required for that operation, and also to obviate to a great extent the danger of straining or injuring the texture of the cloth during the operation of fulling, as liable to heretofore by many of the old machines.

The improved results obtained with and by our machine are mainly due to an improved combination and arrangement of several mechanical devices, such as arranging in combination two fulling-plates having given to them, respectively, reciprocating motions in opposite directions across and on the surfaces of the cloth interposed between them for the purpose of being fulled, and in arranging in combination with said plates feeding and drawing rollers and two series of fulling-rollers, in the manner and for the purposes as hereinafter shown.

Our improvement further consists in mounting the uppermost fulling-plate and the lower series of fulling-rollers in frames adjusted to move in guides in vertical directions, in the manner and for the purposes hereinafter specified.

In order to enable persons skilled in constructing fulling-mills to construct and use our improved machine, we proceed to describe its construction and operation.

A A A is the frame-work of the machine.

B B is an adjustable frame, having vertical guide-bars C C C C, moving in grooves in the frame A.

D is a cross-bar bolted to the frame B and connected by a link, a, to the weighted lever E. The uppermost fulling-plate, F, is attached to the frame B by means of the oscillating bearings G G G G. The pressure of the frame B and plate F upon the cloth being fulled is regulated to a greater or less amount by means of the weighted lever E.

F' is the lower fulling-plate moving in the grooved bearings c c.

The two fulling-plates F and F' have given to them, respectively, reciprocating motions in opposite directions by means of the connecting-bars H and H', receiving motion from crank-pins in the edge of the gear-wheels I and I', one of these gear-wheels being upon the driving-shaft of driving-pulley J, substantially in the manner as herein shown in Figs. 1 and 2.

K K is a frame containing a series of fulling-rollers, d d. (Shown clearly in Figs. 2 and 3.) This frame is permanently bolted to the frame A A.

L L is a movable frame containing a series of fulling-rollers, d' d', and is arranged beneath the frame K. This frame L has a reciprocating rectilinear motion upon wheels running on the race or ways e e, communicated to it by means of the bell-crank M, one end of which is attached to and partakes of the reciprocating motion of the lower fulling-plate, F. The other arm of the crank is connected to the frame K, as seen in Fig. 3. This frame L and series of fulling-rollers have an adjustable motion in vertical direction, the raceway-frame e e being made to move upon guides, and is held in adjusted position by a weight adjusted upon the lever N.

The feeding and drawing rollers w and v of the machine are operated as follows: A stud, g, is affixed to the moving frame L. The forked end of this stud connects with a pin on the feeding-bar O, thus communicating to it a reciprocating motion in connection with that of the frame L. Each end of this bar has a notch connecting it with the lever ends p p of the ratchet-wheels P and P', which are fast to shafts of rollers, the levers having their bear-

ings and moving easily on the shafts of the feed and drawing rollers. The upper ends of the levers have pawls working on the teeth of the ratchet-wheels, and dogs to prevent back motion. The reciprocating motion of the feed-bar O is communicated to the levers p p, thereby causing the pawls to act upon the teeth of the ratchet-wheels and produce a rotary motion of the feed and drawing rollers in the manner well known to machinists.

R, Fig. 4, is a yielding, pliable, or elastic roller or core stock constructed by forming successive concentric layers of canvas cloth, or in any other way by which substantially an elastic roller may be made for the purpose intended. Fitted to the ends of this yielding roller are the canvas collars or caps i i, having eye-holes for passing the lacing-cords through.

When the cloth is to be fulled in length and breadth, it is first treated in the usual way with the fulling-liquid, then rolled on a canvas core roller or cloth-holder. The collars i i are brought up to the ends of the cloth and laced across and around the roll, so as to confine the cloth to the core or cloth-holder. It is now placed between the fulling-plates and power applied to the machine. The time of fulling will vary according to quality of cloth; but after fifteen to twenty-five minutes stop the machine, take out the cloth, and unroll it onto another roller, so as to reverse the sides of the cloth. Then place the cloth as rerolled again between the pulling-plates and full it as before done. This manner of proceeding will cause the cloth to full equally, and the operations are to be repeated as often as the operator may deem necessary. Some pieces of cloth take an hour to full and some pieces take a longer time than that, according to quality of cloth. This mode of fulling cloth possesses the great advantage of preserving the cloth free from straining and other injury.

The peculiar action of the fulling-plates upon the cloth when the cloth is arranged upon an elastic cloth-holder, as above described, causes the cloth to roll with a reciprocating motion between the fulling-plates, and the pressure of the upper plate upon the rolling cloth is variable during its stroke—that is, it is least at the beginning of its stroke, greatest at half-stroke, and least again at end of stroke—so that the cloth is subjected during its treatment between the plates to a succession of increasing and decreasing rolling pressures.

This mode of fulling cloth is peculiarly well adapted to fulling blankets, as by forming them into a roll upon the elastic core or cloth-holder the blankets are fulled equally in all parts and preserve a smoothness of surface and a freedom from all wrinkles not attained by other methods of fulling.

When the cloth is not to be fulled in the

length, but in the width only, the end of the piece is passed over the feeding-roller u, over the lower fulling-plate, F', over and under the drawing-roller v, then between the two series of fulling-rollers, then under the feeding-roller, and the ends laced together, forming an endless web, in the manner as shown by the blue lines in the drawings. In this operation of fulling the cloth is passed by means of the feeding and drawing rollers continuously between the fulling plates and rollers until the operation of fulling is perfected, the cloth meantime being treated with the usual fulling-liquids. The fulling-plates F and F' are continued in motion while fulling the cloth in width only, in order that the lower fulling-plate, F', may give a reciprocating motion to the frame carrying the series of fulling-rollers d' d', and also that the feeding-roller u and drawing-roller v may be actuated in the manner and for the purposes herein set forth; but during said operation of fulling the cloth in width only the upper fulling-plate, F may be and is, by means of the adjustable frame in which it is mounted, raised up from the lower fulling-plate, so that it shall not touch or have any action on the cloth. It will hasten the fulling process by bringing steam in contact with the cloth when passing the series of fulling-rollers. The quantity of frictional contact of the feed and drawing rollers u and v is regulated by a weight adjusted upon a lever, the friction-rollers x and y being mounted in frames having vertical adjustments, and connected with the adjusting apparatus in the manner substantially as seen in the annexed drawings.

Having described our invention, we wish to be understood as laying no broad or exclusive claim to fulling-plates or fulling-rollers, or feeding and drawing rollers, irrespective of their combinations and peculiar mode of operation, substantially as herein described and shown. Nor do we lay any claim to weighted levers for regulating pressure upon fulling plates or rollers or feed and drawing rollers; but

What we do claim as new, and desire to secure by Letters Patent, is—

1. The fulling-plates F and F', when combined one with the other, and having, respectively, reciprocating motions in opposite directions, the uppermost plate having a variable pressure or frictional contact on the cloth's surface, as herein described, both plates being arranged and operating substantially in the manner and for the purposes, as herein set forth and shown.

2. In combination with the fulling-plates F and F', the feed and drawing rollers u and v, and the series of fulling-rollers d' d', the frame carrying the rollers d' d' having a reciprocating motion given to it in horizontal directions and being adjustable vertically, as described the whole arranged and

operating in combination with the fulling-plates, substantially in the manner and for the purposes as herein specified and shown.

3. Arranging and mounting the uppermost fulling-plate, F, and the lower series of fulling-rollers, d' d', in frames that may be adjusted vertically in or upon guides, so that the contact or pressure of the plate and rollers may

be duly regulated to the amount necessary by means of levers and weights, in the manner and for the purposes as herein specified.

JAMES MCKENZIE.
JOHN C. MILLAR.
